C. A. DIES

ADJUSTABLE WRENCH

Filed Sept. 29. 1922

Inventor:

Charles A. Dies.

By Robert Burns.

His Atty.

Witness:

F. J. Gathmann

UNITED STATES PATENT OFFICE.

CHARLES A. DIES, OF CHICAGO, ILLINOIS.

ADJUSTABLE WRENCH.

Application filed September 29, 1922. Serial No. 591,231.

To all whom it may concern:

Be it known that I, CHARLES A. DIES, a citizen of the United States of America, residing at Chicago, in the county of Cook and State of Illinois, have invented a certain new and useful Improvement in Adjustable Wrenches, of which the following is a specification.

This invention relates to that class of wrenches in which a limited movement between the wrench jaws is attained in the initial movement of the operating handle to attain an even and substantial bearing engagement of the jaws upon a nut or other article operated on, and the present improvement has for its objects:—

To provide a formation and assembly of the operating cam member between the operating handle and the movable wrench jaws, adapted to effect maximum closing and opening movements of the wrench jaws with a minimum movement of operating handle of the wrench, in a durable and effective manner.

To provide means for effecting an adjustment or set between the wrench jaws to suit different sizes of work to be operated on, and which is capable of convenient adjustment and effective holding at such adjustment, all as will hereinafter more fully appear.

In the accompanying drawings:—

Fig. 1, is a side elevation illustrating the preferred formation and arrangement of parts in the present improvement.

Fig. 2, is a sectional elevation of the same on line 2—2, Fig. 4, and showing the wrench jaws in a position ready for engagement.

Fig. 3, is a companion sectional elevation showing the jaws in their gripping position.

Fig. 4, is a longitudinal section on line 4—4, Fig. 1;

Fig. 5, is a perspective view of the cam head or block;

Fig. 6, is a side elevation of a modification.

Like reference numerals indicate like parts in the several views.

Referring to the drawings, 1 designates the main jaw member having at one end an angularly disposed work engaging jaw 2, and having a rear portion formed by a pair of cheek plates 3 in spaced parallel relation, formed with a guide-way for the shank portion of the companion jaw member herein-

after described. The cheek plates 3 are also formed with central fulcrum orifices for the hereinafter-described cam head or member by which limited movement of the 60 companion jaw member with relation to the main jaw member 1 is effected. The fulcrum orifices just referred to are of an approximately triangular form with the rear apexes thereof formed by rounded fulcrum 65 sockets 4 and 5, as shown in Figs. 2 and 3.

6 designates the body portion of the companion jaw member above referred to, of an approximately triangular form and having near its forward end a transverse rib 7 70 adapted for sliding engagement with the guideway of the aforesaid cheek plates 3. At one end the body portion 6 has a forwardly extending work-engaging jaw 8 in opposed relation to the jaw of the main 75 member 1 aforesaid, while the rear part of said portion 6 is formed into an open frame or yoke 9, to permit insertion and limited play of the operating cam head above referred to. In the present improvement the opening of 80 the yoke 9 is formed with a forwardly extending fulcrum recess 10 for operative engagement with an operating cam lug of said cam head.

11 designates the operating handle of the 85 wrench, formed of plate sections attached together along their length, with such sections provided with the usual reinforcing ribs as shown. At their forward ends the plate sections are separated to provide a 90 pair of parallel heads 12, 12, between which the cheek plates 3 of the main member 1 are confined and guided in actual use of the wrench. In the present construction the heads 12, 12, have fixed attachment with 95 the operating cam head now to be described.

The cam head heretofore referred to comprises a shaft member 13 having non-circular heads 14 at its respective ends for engagement in similarly formed orifices in the 100 handle heads 12 aforesaid.

15 designates a forwardly extending cam lug formed on the middle portion of the shaft member 13 aforesaid and having operative engagement in the fulcrum recess 7 105 of the jaw member above described to attain independent movement of the same to and from the main jaw member 1.

16 designates a pair of rearwardly extending cam lugs formed on the shaft member 13 at the respective sides of the cam lug 15 and having rounded ends 17 adapted for

bearing engagement in the fulcrum sockets 4 and 5 of the main jaw member 1, and are so positioned as to provide rocking abutments for the cam head in its movements 5 under the influence of the operating handle 11 to effect an engagement or a disengagement of the wrench jaws and the work operated on. By the arrangement of the cam lug 15 at one side of the shaft portion 13 of 10 the cam head and the arrangement of the cam lugs 16 at the other side of said shaft portion 13, as above described, a movement of the operating handle 11, fixedly connected to the cam head, will cause a simultaneous 15 movement of the jaw members 2 and 8 in opposite directions with relation to a median line passing through the shank portion of the cam head, with the combined movement of the jaws amounting to double the amount 20 of turning movement imparted to the cam head by the operating handle 11.

It is within the scope of the invention to make the body portion 6, jaw 8 and yoke 9 of the wrench member aforesaid, of a single piece formation. In the preferred construction shown the wrench member is made in two sections having adjustment to and from each other and adapted for fixed engagement by interengaging teeth 18 in their 30 abutting faces as shown. In such construction the rear section which includes the frame or yoke 9 has limited rearward movement to permit of the disengagement and re-engagement of the parts in the operation 35 of changing the opening or space between the jaws to suit the size of the article to be operated.

19 designate notches formed in the opposite surfaces of the frame or yoke 9, to afford finger holds in effecting a manual adjustment of parts just described.

20 designates a spring arranged to the rear of the body portion 6 aforesaid, the tendency of which is to hold the above described sectional members thereof in the engaged condition and also to provide frictional retardance to a turning movement of said body portion with relation to the operating cam head aforesaid.

50 In the modification shown in Fig. 6, a fixed finger pin or stud 21 on the frame or yoke 9 has movement or play in a T-shape slot 22 in the cheek plates 3 of the main jaw member 1, to attain the heretofore described 55 manual adjustment of the sections of the body portion 6, and at the same time permit of the normal movement of the jaw members with relation to each other and prevent an undue separation thereof.

60 An index mark and scale 23 is provided on the wrench members, as shown in Figs. 1, 3 and 6 as a guide to the operator in a preliminary adjustment of the wrench jaws to suit the size of the work operated on.

65 Having thus fully described my inven-

tion what I claim as new and desire to secure by Letters Patent, is:—

1. In a wrench, the combination of a pair of wrench heads slidingly connected together and having orificed rearward extensions, a cam head arranged in the orifices of said extensions and having a forwardly extending lug for operative engagement with one wrench head and a rearwardly extending lug for operative engagement with the other wrench head and adapted to impart simultaneous movement to the wrench jaws in opposite directions, and a rocking handle fixedly connected to said cam head. 70

2. In a wrench, the combination of a pair of wrench heads slidingly connected together and having orificed rearward extensions, a cam head arranged in the orifices of said extensions and having a forwardly extending lug for operative engagement with one wrench head and with pairs of rearwardly extending lugs for operative engagement with the other wrench head and adapted to impart simultaneous movement to the wrench jaws in opposite directions, 85 and a rocking handle fixedly connected to said cam head. 90

3. In a wrench, the combination of a pair of wrench heads slidingly connected together and having orificed rearward extensions, a cam head arranged in the orifices of said extensions and having a forwardly extending lug for operative engagement with one wrench head and a rearwardly extending lug for operative engagement 100 with the other wrench head and adapted to impart simultaneous movement to the wrench jaws in opposite directions, and a rocking handle fixedly secured to said cam head, one of said wrench heads being formed 105 in sections detachably connected together by interengaging teeth. 95

4. In a wrench, the combination of a pair of wrench heads slidingly connected together and having orificed rearward extensions, a cam head arranged in the orifices of said extensions and having a forwardly extending lug for operative engagement with one wrench head and with pairs of rearwardly extending lugs for operative engagement 110 with the other wrench head and adapted to impart simultaneous movement to the wrench jaws in opposite directions, and a rocking handle fixedly connected to said cam head, one of said wrench heads being formed 115 in sections detachably connected together by interengaging teeth. 120

5. In a wrench, the combination of a main jaw member having at one end a holding jaw and at its rear cheek plates formed with fulcrum orifices, a companion jaw member having at one end holding jaw and at its rear an extension formed with a fulcrum recess, a cam head having a forwardly extending lug for operative engagement with 130

- the fulcrum recess of the companion jaw member and rearwardly extending lugs for operative engagement with the cheek plates of the main jaw member, and a rocking handle having a forked end embracing the aforesaid cheek plates and fixedly secured to said cam head. 5
6. In a wrench, the combination of a main jaw member having at one end a holding jaw and at its rear cheek plates formed with fulcrum orifices, a companion jaw member having at one end holding jaw and at its rear an extension formed with a fulcrum recess, a cam head having a forwardly extending lug for operative engagement with the fulcrum recess of the companion jaw member and with pairs of rearwardly extending lugs for operative engagement with the cheek plates of the main jaw member, and a 10 rocking handle having a forked end embracing the aforesaid cheek plates and fixedly secured to said cam head. 15
7. In a wrench, the combination of a main jaw member having at one end a holding jaw and at its rear cheek plates formed with fulcrum orifices, a companion jaw member having at one end holding jaw and at its rear an extension formed with a fulcrum recess, a cam head having a forwardly extending 20 lug for operative engagement with the fulcrum recess of the companion jaw member and rearwardly extending lugs for operative engagement with the cheek plates of the main jaw member, and a rocking handle having a forked end embracing the aforesaid cheek plates and fixedly secured to said cam head. 25
8. In a wrench, the combination of a main jaw member having at one end a holding jaw and at its rear cheek plates formed with fulcrum orifices, a companion jaw member having at one end holding jaw and at its rear an extension formed with a fulcrum recess, a cam head having a forwardly extending lug for operative engagement with the fulcrum recess of the companion jaw member and with pairs of rearwardly extending lugs for operative engagement with the cheek plates of the main jaw members, a rocking handle having a forked end embracing the aforesaid cheek plates and fixedly secured to said cam head, the companion wrench head being formed in sections detachably connected together by interengaging teeth. 30
9. In a wrench, the combination of a main jaw member having at one end a holding jaw and at its rear cheek plates formed with fulcrum orifices, a companion jaw member having at one end holding jaw and at its rear an extension formed with a fulcrum recess, a cam head having a forwardly extending lug for operative engagement with the fulcrum of the companion jaw member and with pairs of rearwardly extending lugs for operative engagement with the cheek plates of the main jaw member, and a rocking handle fixedly connected to said cam head, one of said wrench heads being formed in sections detachably connected together by interengaging teeth, and a spring adapted to hold said sections in engagement. 35
10. In a wrench, the combination of a main jaw member having at one end a holding jaw and at its rear cheek plates formed with fulcrum orifices, a companion jaw member having at one end holding jaw and at its rear an extension formed with a fulcrum recess, a cam head having a forwardly extending lug for operative engagement with the fulcrum recess of the companion jaw member and with pairs of rearwardly extending lugs for operative engagement with the cheek plates of the main jaw members, a rocking handle having a forked end embracing the aforesaid cheek plates and fixedly secured to said cam head, the companion wrench head being formed in sections detachably connected together by interengaging teeth, and a spring adapted to hold said sections in engagement. 40

Signed at Chicago, Illinois, this 26th day of September, 1922.

CHARLES A. DIES.
